Patented Mar. 13, 1917.

UNITED STATES PATENT OFFICE.

RYOTARO NOBUOKA, OF PORTLAND, OREGON,

SIGNALING DEVICE.

1,219,346.

Specification of Letters Patent.

Patented Mar. 13, 1917.

Application filed January 24, 1916. Serial No. 74,025.

To all whom it may concern:

Be it known that I, RYOTARO NOBUOKA, a subject of the Emperor of Japan, and a resident of the city of Portland, county of 5 Multnomah, State of Oregon, have invented a new and useful Improvement in Signaling Devices, of which the following is a specification.

This invention relates generally to automobile signaling devices, and has particularly to do with semaphore arms by the dropping of which the driver of a car may signal the direction in which he is to turn to a pedestrian or driver of another car.

One of the main objects of my invention is to provide an improved form of semaphore arm signal, in which the signal arm itself comprises a plurality of leaves, adapted to be spread into a fan-like shape when 20 in active use, so as to provide a large surface indicator, but which, when not in use, will fold up into a body of relatively small surface, inconspicuous in appearance and occupying but small space.

The principal features of my invention consist in the construction, arrangement and operation of parts by means of which I attain the object of my invention. These features are all fully set forth in the accompanying drawings, in which:

Figure 1 is an elevation showing my device as used in connection with an automobile, the signal being set;

Fig. 2 is a plan view of the casing in which the pivoted leaves of the signal arm are mounted;

Fig. 3 is a vertical section on the line 3—3 of Fig. 2;

Fig. 4 is a larger-sized sectional elevation 40 of the rotary housing in which the pivoted ends of the leaves are incased; this view is a side elevation viewed from the same point as Figs. 1 and 3;

Fig. 5 is a view similar to Fig. 4, but 45 viewed from the opposite side; and

Fig. 6 is a view showing the parts of Fig. 5 in elevation, instead of section.

A casing, *a*, having one side open is provided with a circular head *b*. The latter is 50 made with flanged members *c* to which are attached clamps *d*, the latter being adapted to engage the side member *e* of a windshield *f*, so as to hold the casing securely in vertical position at the side of the automobile. One side of the head, *b*, is pro-

vided with a circular slot *g* (see Fig. 3). The other side of the head is provided on its inner side with a circular groove *h*, the position of which is indicated by the broken lines *h* of Fig. 4.

A cylindrical housing *i* is pivoted within the head *b* on the pivot *j*. Said housing is provided on one outer side with a lateral pin *k*, extending outwardly through the slot *g*, and a lateral pin *l* extending inwardly between the sides of the housing.

The leaves of the signal arm are indicated by *m*, *n*, *o*, *p*, and said leaves are loosely mounted within the housing on the pivot *j*. The leaf *m* is provided with slots *m'*, *m*², the leaf *n* with slots *n'*, *n*², the leaf *o* with slots *o'*, *o*², and the leaf *p* with slots *p'*, *p*². When the leaves are in normal, inactive position, the slots will be superposed upon each other as shown in Figs. 4 and 5.

Fixed on the outer side of the leaf *p* is a small plate *q*, provided with oppositely extending pins *s*, *t*. See Fig. 5.

The pin *s* extends inwardly through the superposed slots *m*², *n*², *o*² and *p*² and its outer end projects into the circular groove *h*. The pin *t* extends outwardly through a bayonet slot *u* in the adjacent side of the housing *i*. Furthermore, the lateral pin *l* of the housing *i* is located so as to extend through the slots *m'*, *n'*, *o'* and *p'*.

The periphery of the housing *i* is partially open, as shown in Figs. 4 and 5, so as to allow the leaves to have a slight relative rotary movement with respect to each other and the housing. This movement permits the leaves to assume a fan-like shape.

Fixed on one side of the casing, *a*, is a bearing *v*, in which is clamped one end of a tubular, flexible conduit *w*. The other end 95 of this conduit is fixed to the end of a cylindrical bearing *x*, which is clamped to the steering wheel column *y* by the clamp *z*. A reciprocable plunger *2*, movable within the bearing *x*, is provided with an operating 100 finger *4*, and a transmission wire *5*, longitudinally movable within the stationary conduit *w*, has one end fixed to the plunger *2*, and the other end to the pin *k* of the housing *i*. See Fig. 3.

The general operation of this signaling device is as follows:

Normally the parts are positioned as shown in Fig. 4, the leaves being folded into vertical position within the casing *a*. To set 110

the signal, the plunger 2 is pulled out to the position shown in Fig. 1. This movement causes a pull to be exerted on the wire 5, and, as a consequence, the housing *i* will be rotated clockwise through an angle equal to the central angle of the circular groove *h*, the ends of the latter forming stops for the pin *s*.

Referring to Fig. 4, when the housing *i* is rotated, the pin *l*, being rigidly fixed between the sides of said housing, will first bear against the end of the slot *m'* and rotate the leaf *m* a slight distance before contacting with the end of the slot *n'*, whereupon the leaf *n* will be rotated also, the operation progressing until the pin *s* contacts with the end of the groove *h*. The leaves will then be arranged in a fan-like form as shown in Fig. 1, and form a conspicuous signal to indicate that the machine is about to stop or turn. In the construction shown, a white hand is painted on the red background of the leaves, and this renders the signal very effective for the purpose of automobile signaling. However, for railway, or other signal work, other forms and configurations of the leaves may be used.

I claim:

1. A signaling device comprising a pivot member, a plurality of parallel leaves mounted loosely on the pivot member, said leaves being provided with progressively graded slots so located that when the leaves are superposed the corresponding ends of the slots will be in alinement, a member revolvable about the pivot member, said member projecting through the slots, means for revolving the member about its pivot, and means for limiting the degree of such revolution. 30

2. A signaling device comprising a hollow casing, a housing pivoted in said casing, a plurality of parallel leaves mounted loosely on the pivot of the housing, said leaves being provided with progressively graded slots so located that when the leaves are all superposed the corresponding ends of the slots will be in alinement, a lateral pin member secured to said housing, said member projecting through the slots, means for rotating the housing about its pivot, and means for limiting the degree of such revolution. 40 45 50

RYOTARO NOBUOKA.
